UNITED STATES PATENT OFFICE

2,597,293

REFRIGERATED WATER SYSTEM

Eugene J. Coletti, Chicago, Ill.

Application August 5, 1950, Serial No. 177,925

2 Claims. (Cl. 62—141)

1

This invention relates to refrigerated water systems, and more specifically to the drinking water systems such as required, for example, in Pullman cars and similar installations wherein it is desirable to provide uniformly cool water at any one of a multiplicity of outlets.

In the drinking water systems of the most modern types presently employed in conventional sleeping cars, the individual taps or outlets located in the various compartments or rooms of the car are all connected to a common recirculating system. Ordinarily, this system is supplied with water from a refrigerated cooler provided near one end of the car. In the most common present construction, the cars are provided with a compartment about six feet high and nine or ten inches square, in which this cooler, as well as the compressor, condenser, evaporator and fan of the refrigerating system are installed. Obviously, the size and shape of this compartment, which is dictated by the limitations of space available within the car, requires expensive equipment especially designed for such installations.

This arrangement has also shown itself to be disadvantageous in several other respects, particularly since the fan and condenser of the refrigerating system are located within the car and adjacent the rooms and compartments thereof, where they are not only difficult of access for repair, inspection and service, but where they are in the proximity of an unusually high concentration of lint in the air, and in a position where the noise of operation of the mechanical parts of the unit is irritating to passengers in the car.

In further explanation of the above, it may be pointed out that since it is essential to have adequate circulation of air through the condenser of the refrigerating unit, there appears to be no feasible way of effectively soundproofing the unit or its housing sufficiently that the noise of its operation will not disturb passengers in the car. At the same time, the presence of large quantities of bed linens, etc., within the car, together with the activity of many people within a comparatively small area, and the constant abrasion of carpet, upholstery and clothing, gives rise to an extremely high lint content in the air. This is a source of constant trouble in conventional systems, since it tends to accumulate on the fins of the condenser of the refrigerating system so rapidly that repeated service is required to keep the units in condition for efficient operation.

2

The present systems are further objectionable in that the temperature of the water available in the various compartments is not uniform, even with a well insulating recirculation system, since there are always enough thermal losses to bring about a drop of several degrees between the temperature of water available at a tap close to the cooling unit and the water available at a more remote outlet.

10 It is, therefore, the general aim of the present invention to provide a novel and improved water cooling system wherein the disadvantages inherent in conventional installations are largely overcome, so that water may be supplied to a multiplicity of outlets at a more constant temperature, yet with less expensive equipment than heretofore required.

20 A further object of the invention is to provide a water cooling system which is of greater efficiency than those heretofore proposed, so that a higher capacity unit may be employed at less expense than heretofore. Another object is to provide a system capable of operation with less wear on the component parts than in present apparatus, and designed to operate so silently as to eliminate any disturbance of people in a car equipped with the system.

25 Further objects of the invention are to provide a cooling system particularly suited to use in a railroad passenger car or the like, wherein the mechanical parts of the refrigerating system are easily accessible for repair, replacement or service without disturbing passengers in the car, and wherein the system is so designed as to be unaffected by the presence of lint in the air inside of the car, and to utilize less interior space of the car.

30 In the present invention the above objects are brought about by a unique water cooling system which departs from the prior practice of providing a unitary water cooler with a supply line extending therefrom to the various outlets of the system, and provides a system wherein the evaporator of the refrigerating unit is co-extensive with the water supply line and in heat exchanging relationship therewith throughout its length, so that the refrigerating action takes place along the entire length of the line, rather than at the point of supply only. By this means 35 it is entirely feasible to provide a system wherein water cooled to the optimum temperature will be available at any and every tap along the entire supply line, even without utilizing a recirculating system to maintain uniformity of temperature. The system is equally applicable,

however, to any type of recirculating system, and a preferred embodiment of the invention utilizing the present teachings in connection with the recirculating system of a railroad sleeping car is described in connection with the drawings of this application, wherein:

Figure 1 is a diagrammatic illustration of a preferred form of the present invention; and

Figure 2 is a detail sectional view of the junction between the water supply line of the system and the refrigerant line of the evaporator employed thereby.

The system here disclosed is adaptable to installation in hotels, residences, office buildings and many other locations, but is particularly well suited to installation in railroad sleeping cars, for example, and will accordingly be described in connection with a specific illustration of such an installation.

The car, generally designated as 10, includes an undercarriage or frame comprising beams 11 to which trucks or wheels 12 are secured in the conventional manner. It will be understood that while no detail is shown in the present drawings, such a car has a number of separate rooms or compartments, each of which is provided with a faucet or tap such as the outlet valves 13, 14, 15 and 16.

It is obviously desirable to supply each of these multiplicity of outlets with fresh, clean refrigerated water at a uniform temperature. Moreover, it is desirable that the water supplied to these taps be available instantly upon opening the tap, without necessity of drawing off a quantity of water before water of the desired temperature reaches the outlet.

To this end, the valves 13, 14, 15 and 16 are each connected to a common water supply line 18, which extends from a discharge outlet 19 of a recirculating pump 20. The supply line 18 is a part of a closed recirculating system including a return line 21, which extends from the outer extremity of the supply line 18 to the inlet 22 of the recirculating pump. The recirculating system is insulated throughout by an insulating layer 24 over the supply line and over the return line, and the recirculating pump may be enclosed within an insulating housing if desired. All of these parts are within the railway car, however, where they are not subject to extremes in temperature, so that the entire recirculating system is adequately protected against freezing.

Water drawn from any of the outlets of this recirculating system is replenished through a supply connection 25 which extends from a reservoir 26 through a check valve 27 and into the return line 21 from whence it is drawn through the pump 20 and discharged into the supply line 18.

The water from the reservoir 26 may be forced into the system by gravity if the reservoir is located at a sufficient height, but with the reservoir located below the car and suspended from the frame members thereof as shown, any conventional means (such as the compressed air valve 27) may be employed to force the water from the reservoir into the recirculating system. It will be understood, of course, that if the water supply reservoir is positioned exteriorly of the car as shown, adequate precautions will be taken to prevent freezing of water in severe weather, as by provision of additional insulation or an internal heater (not shown). Also, a filler cap 28 or other connec-

tion is provided for replenishing the supply of water in the reservoir.

The present system differs from systems heretofore employed primarily because of the fact that the water is refrigerated throughout substantially the entire length of the recirculating system rather than at a single source of supply. To accomplish this, the car is provided with a refrigerating unit 30 comprising a compressor 31 and condenser 32, both of which may be conveniently mounted on a single base 33 and detachably suspended on the undercarriage 11 of the car, as by the bolts 34. As is conventional in such units, the coils of the condenser may terminate in an expansion valve 35, from which a refrigerant supply line 36 leads to a coupling 37 on the lowermost end of a tube 38 extending through and sealed into the exterior wall of the line 18, as indicated at 39 (Figure 2). The tube 38 comprises the evaporator of the refrigerating system, and this tube, which has an outside diameter considerably smaller than the inside diameter of the water supply line 18, extends through the recirculating system the entire length of the supply line 18 and, as shown, continues through the rear line 21 to an exit connection 41 adjacent the inlet 22 of the recirculating pump. From the point 41 the refrigerant is fed back to the inlet 42 of the compressor through a return line 43 coupled to the inlet line 44 of the compressor by a detachable coupling 45.

From the foregoing it will be apparent to those skilled in the art that the cooling unit of the present system does not cool the water at one point only (as is the practice in conventional systems), but is so designed that the cooling takes place along the entire length of the supply and return lines, so that the system tends to maintain a high degree of uniformity of temperature at all points in the line, irrespective of whether the pump 20 is operated to keep the water in constant circulation.

It is to be further noted, however, that even if relatively large quantities of water are drawn off from the several taps in the system, adequate cooling is provided to water supplied thereto, since the greatest cooling effect of the evaporator 38 occurs in the portions closest to the expansion valve, and this portion of the evaporator is positioned between the pump 20 and the outlets of the supply line, so that the water entering the line is adequately cooled before it reaches the tap. A thermostat 46 may be positioned in the line to control the operation of the refrigerating system, as is conventional in refrigeration practice.

It should be observed that with a system constructed in accordance with the present teachings, all difficulties arising from the presence of the refrigerating mechanism within the car are eliminated, and it follows that operation of this mechanism cannot disturb occupants of the car by reason of the noise produced, and that the fins and cooling coils of the condenser will not be subjected to high concentrations of troublesome lint laden air. The ordinary dust encountered on a railroad right-of-way is not particularly bothersome in this respect, since it has very little material having fibers of sufficient length to cause objectionable clogging.

The system here disclosed is additionally advantageous in that the positioning of the refrigerating unit at a point outside of the car makes it feasible to use any conventional type

of compressor and evaporator, rather than one specifically designed for the limited space available in an interior compartment of the car, and also renders the operating parts of the refrigerating unit easily accessible for inspection, repair or replacement. As a matter of fact, the entire unit may be quickly and easily removed merely by loosening the bolts 34 and detaching the connections 31-45. An entirely new unit may thus be put in position, connected and placed in operation without disturbing occupants sleeping in the various compartments of the car.

With all of the above, the system here disclosed accomplishes more efficient cooling than heretofore obtained, since substantially the entire external surface of the evaporator is in direct contact with the liquid being cooled. This reduces thermal losses to a marked degree, and thus accomplishes greater efficiency in cooling than heretofore practicable in such installations.

Having thus described my invention, what I claim as new and desire to secure by United States Letters Patent is:

1. In a circulating refrigerated water system for a railway car, the combination of a closed recirculating cool water circuit comprising a supply line having a plurality of water outlets spaced apart along its length, a circulating pump having an outlet discharging water into said lines under pressure to maintain flow therethrough, and a return line extending from said supply line to the intake of said pump, with said supply line, circulating pump and return line located within the said railway car; a water supply connection for said recirculating circuit,

and a refrigerating system located exteriorly of the car, with an evaporator comprising a refrigerant line extending substantially the entire length of the water supply line and in intimate heat exchanging relationship therewith.

2. In a circulating refrigerated water system for a railway car, the combination of a closed recirculating cool water circuit comprising a supply line having a plurality of water outlets spaced apart along its length, a circulating pump having an outlet discharging water into said lines under pressure to maintain flow therethrough, and a return line extending from said supply line to the intake of said pump, with said supply line, circulating pump and return line located within the said railway car; a water supply connection for said recirculating circuit, and a refrigerating system located exteriorly of the car, with an evaporator comprising a refrigerant tube smaller than the water line and extending therethrough with the exterior walls of the tube in direct contact with the water in the supply line.
